UNITED STATES PATENT OFFICE.

EMIL B. GUNTHER, OF ALTADENA, CALIFORNIA.

FLOOR SURFACER.

Application filed July 5, 1922. Serial No. 572,816.

To all whom it may concern:

Be it known that I, EMIL B. GUNTHER, a citizen of the United States, residing at Altadena, in the county of Los Angeles and State of California, have invented new and useful Improvements in Floor Surfacers, of which the following is a specification.

This invention relates to surfacing apparatus and more particularly to floor surfacers, and has for an object to provide a floor surfer involving a caterpillar surfacing medium.

An object is to provide a machine which may be manually or power driven over a floor for the effective smoothing of the flooring to remove unevennesses as between the floor boards, and therefore to bring the edges and abutting ends of the boards flush. It is an object to provide a machine of this type employing an endless series of cutting members, and to provide means for pressing cutting members to their effective position. Another object of the invention is to provide a machine employing an endless belt of cutters which are adapted to be rendered effective with different degrees of pressure. Another object is to provide means for quickly, accurately and readily adjusting the parts to effective position.

Another object is to provide a machine convertible from a rough surfacing tool into a sander, and further to provide means for quickly and effectively tensioning a sanding cylinder strip.

Other objects and advantages of the invention will be made manifest in an embodiment illustrated in the accompanying drawings, wherein:

Figure 1 is a side elevation of the left-hand side of the machine; showing it tilted for mechanical drive.

Fig. 2 is a bottom plan, parts being in section.

Fig. 3 is a detail, longitudinal, sectional view of a part of the frame and showing the caterpillar tool belt.

Fig. 4 is a side elevation of the right-hand side of the machine in a position corresponding to Fig. 1.

Fig. 5 is a side elevation of the right-hand side showing the machine as released and positioned for manual propulsion.

Fig. 6 is a plan of the machine as adapted for sanding.

Fig. 7 is a right-hand side elevation of the adapted machine.

Fig. 8 is a longitudinal section of the sanding drum.

Fig. 9 is an end view of Fig. 8, showing 60 the adjustable section of the drum.

Fig. 10 is a plan of the bottom of a group or unit of the cutters.

Fig. 11 is a side elevation of a cutter group unit.

Fig. 12 is a top plan and partial section of a cutter unit.

Fig. 13 is an end view of the cutter unit of Fig. 11.

Fig. 14 is a side elevation of a unit skeleton; 70 the cutting blades being removed.

Fig. 15 is a bottom plan of the unit skeleton.

Fig. 16 is an end view of the skeleton shown in Fig. 14.

Fig. 17 is a side elevation of one of the cutting blades.

Fig. 18 is a plan showing a blank of one form of caterpillar spring device.

The machine is embodied in a structure 80 consisting of a suitable frame which may have parallel side flanges 2 cross connected at the top by a top plate 3, thus forming an inverted channel-shaped box. Transversely arranged upon the forward end of the box is a shaft 4 having its outer ends provided with discs 5, journaled for rotation in the sides 2. The lower portions of the discs may be supported in bearing straps 6. The discs 5 are provided with cranks 7, which are co-axial and carry jack wheels 8. The crank shaft 4 is designed to be rotated for raising and lowering the front end of the box and this is accomplished by suitable means, which may consist of a sprocket chain combination 10,

including a sprocket wheel 11 fixed on a transverse shaft 12 journaled in the sides 2 of the box. On one end of this shaft there is secured a lever 13 which extends 95 upwardly and is provided with a locking ratchet 14 to engage a toothed segment 15 concentrically fixed to one side 2 of the box,

so that by throwing the lever 13 forwardly or rearwardly as desired, the crank shaft 100 4 is rotated in its bearings and the frame is lifted or lowered accordingly, while the jack wheels 8 rest upon the supporting floor.

Secured to the rear end of the frame or box in any suitable manner is a rearwardly 105 4

rotated in its bearings and the frame is lifted or lowered accordingly, while the jack wheels 8 rest upon the supporting floor.

Secured to the rear end of the frame or box in any suitable manner is a rearwardly 110

extending and centrally arranged trailer wheel 17, which may be mounted in the rear lower end of a bracket 18 fastened to the top of the box structure. It will be seen that the vehicle is thus supported ordinarily on the two jack wheels 8 and the trailer wheel 17, all of which are free and not positively driven.

Across the front end of the frame or box 10 there is arranged a transverse shaft 20, which is preferably longitudinally adjustable as by means of screws 21 passing through the shaft and which are arranged in longitudinal slots 22 provided therefor in the front ends 15 of the side plates 2. Upon this shaft 20 there is secured a drum 23 disposed between the sides 2 of the box and the drum is provided at its ends with sprocket wheels 24, which are provided with sprocket chains 25 extending 20 rearwardly and close to the inside faces of the sides 2. The inner and rear ends of the sprocket chains or belts 25 engage sprocket wheels 26, which are secured upon the ends of a rear drum 27, which is secured 25 on a transverse shaft 28 journaled in the box. One end of the shaft 28 is provided with a driving sprocket 29, disposed outside of the adjacent box wall 2, and from this sprocket runs belt 30 leading upwardly to a 30 pinion 31 secured on a counter-shaft 32, mounted in pillars 33 provided on the top 3 of the box.

This counter-shaft is driven by power from any suitable source, such for instance, 35 as a motor M mounted on the rear end of the box and the shaft of which is provided with a sprocket pinion 34, driving a belt 35 leading forwardly to and engaging a sprocket wheel 36 fastening on the counter-shaft 32. From this it will be seen that the 40 drum shaft 28 may be positively driven.

For manually propelling the vehicle, a suitable handle or handles H may be provided and extended to the rear for convenient grasp by the operator. It is desirable 45 to provide means for a mechanical drive of the vehicle by power derived from the motor M. It is understood that any suitable character of motor, as gas or electric, may be 50 employed.

To provide for mechanical propulsion, the shaft 32 is provided with a spiral gear 40, engaging a complementary gear 41 secured on the forward end of a longitudinal shaft 42, which is provided with a bevel pinion 43 on its rear end. This pinion engages another pinion 44, suitably mounted and combined with a sprocket wheel 45, whereby power is transmitted by means of a sprocket 60 chain 46 extending down to a sprocket wheel 47, which is secured upon a driven shaft 48. This shaft is arranged across the rear end of the box or frame and is designed to oscillate as to the frame. The shaft 48 is of 65 tubular form and is rotatively mounted upon

a rod 49, which is fixed in rearwardly extending lever arms 50. These arms extend forwardly and upwardly and are pivoted on bearings 51 in the sides 2 of the box, and the levers also extend rearwardly and have 70 foot pedals 50', so that the operator may, while standing with one foot on the top of the box, also place a foot on one or the other of the end pedals 50' and thus swing these levers with the shaft 48 downward on their 75 pivots. One of the levers 50 is provided with a forwardly extending end 50", which is designed to swing up and engage the stop 52. This action occurs when the pedals 50' are pressed down. The shaft 48 is normally 80 pressed upwardly by a spring 53 or suitable means and this serves to lift wheels 54 that are mounted tight on the shaft 48 up out of contact with the floor surface, as is shown in Fig. 5. Therefore, the wheels 54 may be 85 constantly driven, but are held in ineffective position by the springs 53 until such time as the pedals 50' are pressed down. Then these wheels become effective and drive the vehicle. The downwardly pressed levers 50 thus serve to rock on the axis of the wheels and lift the rear end of the vehicle and the trailer wheel 17, carrying the latter out of bearing on the surface.

An important feature of the present invention resides in the means for scraping the surface to be treated. Preferably such means is built up in the form of an endless traveling belt, which includes a number of yieldingly mounted scraping or sawing blades or 90 cutters.

One form of cutter is illustrated in Fig. 17 as consisting of a blade 60 of suitable material, having an effective toothed or roughened edge 61, each end of the blade 105 being provided with a shoulder 62, and the longitudinal edge that is parallel to the toothed edge 61 is notched as at 63. A number of such blades is mounted upon a carrier, which may be termed a skeleton, and a form 110 thereof is shown as including a set of parallel ribs 65, suitably spaced by fillers 66, engaging end lugs 65' which are perforated to receive respective bushings 67 which pass through the fillers 66. The bushings are 115 suitably riveted or otherwise fastened in a way adapted to receive transversely extending pivot rods 70, a number of which is arranged in parallel order and upon which rods the units of cutters in the skeletons are 120 arranged in alternate relation as shown clearly in Fig. 2, thus forming an endless traveling belt which is built up of the cutter units.

The space between parallel ribs 65 enables 125 the insertion therein of a group of the cutter blades 60, as is clearly shown in Figs. 10 and 12; the toothed edges of the cutter blades projecting beyond the longitudinal outer edge of the ribs so as to be presented 130

to and to effectively engage the surface to be treated. The ribs 65 are of such depth as to bear upon the front and rear drums 23 and 27, around which the built up belt 5 or cutter units travel. The lugs 62 of the cutter blades project longitudinally and bear upon the contiguous fillers 66.

Preferably the cutters 60 are yieldingly mounted and accordingly means are provided for yieldingly thrusting the blades 60 in one direction, which movement is limited as the lugs 62 engage the fillers 66. In Figs. 11 and 12 there is shown a spring device having transverse arms 72 which are provided with tubes 73 and these are pressed down against the back edges of the blades 60. The spring bars 72 have radial arms 74 extending from loops 75 which are shown as arranged on any suitable support, as for instance, a cotter pin 76 which passes through holes 65^a provided in the ribs 65. This device, it will be seen, serves to yieldingly support the cutters 60 in their positions between the parallel ribs 65.

Another form of cutter support is shown in Fig. 18 in which a leaf spring blade 80 is provided with oppositely extending spring fingers 81, each of the fingers being adapted to engage a group of the cutter blades 60 between the parallel ribs 65. In this manner each end of each group of cutter blades is yieldingly supported independently of the action of the other groups of cutters. In other words the spring fingers 81 act individually upon the contiguous ends of groups of cutters.

When the belt of units has been connected up and mounted upon the drums 23 and 27, the lower stretches of the belt sags down toward the floor and the degree of surface of contact of the belt upon the floor may be readily determined by rotating the crank shaft 4 to throw the same up or down and correspondingly raise or lower the frame 45 or box in which the belt is supported.

During operation of the vehicle it may be propelled manually when the jack wheels 8 and the trailing wheel 17 carry the load. To make a very light cut the jack wheel 50 spindles are so turned as to nearly lift the teeth of the cutter blades from the floor F. The function of these teeth is to cut or grind off the irregularities that may exist between the meeting edges and ends of the 55 flooring. In other words, it is the function of the machine to bring the flooring into a smooth superficial surface at the joints of the floor boards. To increase the amount of cut the jack wheel shaft is so rotated 60 as to further lower the frame.

If it is desired to propel the vehicle by motor power, then the operator applies pressure to the pedals 50' and this results in springing the traction wheels 54 down 65 to the floor surface. The traction wheels

being positively driven, cause the vehicle to be propelled thereby. The scraping belt is adjusted as above described, whether the vehicle is manually or motor propelled.

The machine is constructed and arranged to be readily adapted either for the scraping of the floor as by the elements above described, or it may be utilized for sanding the floor. In the latter case the scraping belt is removed and there is utilized in its stead a sanding drum 90. This drum has sections 91 and 92, the former being keyed on a shaft 93 and the latter being rotative thereon and set out in suitable position as by a set-screw 94 accessible in one end of the drum section 92. The drum is of uniform diameter from end to end and at one end thereof there is attached the end 95 of a helix 96 of friction material, such as sand paper or cloth. This helix is wound around the drum from the fixed end 95 in section 91 onto the section 92, where the end 97 of the strip is attached. After the drum has been wound with the sand paper, the section 92 is released and then rotated in such direction as to tension the strip 96 of sand paper so that this will be drawn tightly around the drum and then the section 92 is fastened up on the shaft 93. The sanding device is readily attached to the machine by means of bracket arms 100, in the forward ends of which the shaft 93 is journaled. The brackets 100 are shown as resilient and are fastened by suitable clamps 101 on the sides of the box. One end of the shaft 93 is provided with a sprocket wheel 102 engaged by the sprocket chain 103, which is driven by a wheel 104 on the counter-shaft 32. The sand drum 105 may be moved into bearing upon the floor surface by the operation of the foot pedals 50', whereby the front end of the machine is tilted down while the rear end is tilted up.

The sanding cylinder sections 91 and 92 are shown as provided with a cushioning or elastic jacket 91^a, around which the abrasive helix is wrapped. This, therefore, provides for a cushioning or pliant support for the sanding material. The sanding drum or cylinder can be pressed toward the surface to be treated by manipulation of the vehicle by means of the handles 14, application of force to which will press or lift the sand drum as to the floor surface.

The unit-bearing pivot rods 70 are preferably of such diameter as to permit their bending and therefore enabling the belt stretches which bear upon the floor like a mat, to flex conformably with undulations of the flooring.

It is understood that, if necessary, the units of saw blades may be slightly offset with respect to its predecessor in line, so that the blades will not register one behind the other. This offsetting will prevent, there-

fore, the deep scoring or grooving of the floor boards.

Various modifications may be resorted to within the scope and spirit of the invention 5 as here claimed.

What is claimed is:

1. A floor surfacer having an endless traveling link-mat chain of surface-scraping means.
- 10 2. A floor surfacer having an endless traveling link-mat chain of surface-scraping means and consisting of parallel rows of groups of blades; the groups of one row being offset with respect to the groups of the next contiguous row.
- 15 3. A floor surfacer having an endless traveling mat-like chain of surface-scraping means presenting in unending continuity effective scraping elements.
- 20 4. A floor surfacer comprising a wheeled vehicle, an endless traveling mat-like chain of scraping units mounted on the vehicle and having a sagging portion operative to scrape the floor, the units being arranged in transverse rows, and means for regulating the effective area of contact of the sagging portion.
- 25 5. A floor-surfacing machine, including a wheeled frame and a scraping means mounted on the vehicle and comprising a chain formed of transverse flexible rows of scraping units operative when the belt sags and is in engagement with the floor to be scraped.
- 30 6. A floor-surfacing machine, including a frame, an endless traveling scraping belt mounted upon the frame, bearing wheels upon which the frame is supported in free rolling position, and power-driven bearing wheels adapted to be shifted into operation to propel the vehicle.
- 35 7. A floor-surfacing machine, including a frame, an endless traveling scraping belt mounted upon the frame, bearing wheels upon which the frame is supported in free rolling position, power-driven bearing wheels adapted to be shifted into operation to propel the vehicle, and means for regulating the effective contact by said scraping belt with the floor surface, while supported on the driving wheels.
- 40 8. A floor-surfacing machine, including a frame, an endless traveling mat-like chain of scraping units mounted upon the frame, bearing wheels upon which the frame is supported, power-driven bearing wheels adapted to be shifted into operation to propel the vehicle, and means for driving the scraping chain, including drums carrying said chain and connected by drive elements.
- 45 9. A floor-scraping machine, including a wheeled vehicle, an endless traveling mat of units having means for scraping a floor surface, said mat having a downwardly sagging transversely pliable portion to approach the

floor, and means for adjusting the degree of 65 contact of the effective sagging portion.

10. In a floor-surfacing machine, an endless traveling belt consisting of units of link members, and tooth blades movably carried by the units and operative for scraping a 70 floor surface.

11. In a floor-surfacing machine, an endless traveling belt consisting of units of link members, tooth blades carried by the units and operative for scraping a floor surface, 75 and means for yieldingly pressing the blades to their effective position.

12. A floor surfacer having an endless traveling mat-like chain of surface-scraping means, the chain consisting of units of 80 gangs including independently movable toothed blades.

13. A floor surfacer having an endless traveling mat-like chain of surface-scraping means, the chain consisting of units of gangs 85 including independently and yieldably movable toothed blades.

14. A floor-surfacing machine including a frame having wheels on which it is freely rollable, an endless mat-like flexible scraping means presenting an effective face to the floor to be surfaced, means for driving the scraping means, and foot operated means for raising and lowering the frame so as to tilt on certain of the wheels thereof for lowering propelling wheels, the foot operated means including levers fulcrumed between their ends on a wheeled shaft, said levers being connected to the contiguous end of the frame.

15. A floor-surfacing machine including a frame having wheels on which it is freely rollable, an endless mat-like flexible scraping means presenting an effective face to the floor to be surfaced, means for driving the scraping means, and foot operated means for raising and lowering the frame so as to tilt on certain of the wheels thereof, the foot operated means including levers fulcrumed between their ends on a wheeled shaft, said levers being connected to the contiguous end of the frame, the wheels of said shaft being power driven.

16. In a floor-surfacing machine, a wheeled frame, an endless traveling scraping chain operatively mounted on the frame, and means for raising and lowering the frame including discs rotatably journaled in the sides of the frame and being axially connected for concurrent rotation, said discs having eccentric portions forming axles for bearing wheels of the frame.

17. In a floor-surfacing machine, a wheeled frame, an endless traveling scraping chain operatively mounted on the frame, means for raising and lowering the frame including discs rotatably journaled in the sides of the frame and being axially con-

nected for concurrent rotation, said discs having eccentric portions forming axles for bearing wheels of the frame, and means for rotating the discs in their bearings and including a transmission mechanism connected to their shaft.

18. In a floor-surfacing machine, a scraping unit consisting of a set of parallel spaced and fixedly connected rib-like members, and scraping cutters arranged in groups between the said rib-like members.

19. In a floor-surfacing machine, a scraping unit consisting of a set of parallel spaced and fixedly connected rib-like members, scraping cutters arranged in groups between the said rib-like members, and means for yieldingly thrusting the scraping cutters toward an effective position.

20. In a floor-surfacing machine, a scraping unit consisting of a set of parallel spaced and fixedly connected rib-like members, scraping cutters arranged in groups between the said rib-like members, means for yieldingly thrusting the scraping cutters toward an effective position, and means for pivotally connecting transverse rows of the units to form an endless mat-like chain.

21. In a floor-surfacing machine, a scraping unit consisting of a set of parallel spaced and fixedly connected rib-like members, scraping cutters arranged in groups between the said rib-like members, means for yieldingly thrusting the scraping cutters toward an effective position, and means for pivotally connecting transverse rows of the units to form an endless mat-like chain, the units of successive rows being relatively offset.

22. In a floor-surfacing machine, a scrap-

ing unit consisting of a set of parallel spaced and fixedly connected rib-like members, 40 scraping cutters arranged in groups between the said rib-like members, means for yieldingly thrusting the scraping cutters toward an effective position, and flexible means for pivotally connecting transverse rows of the 45 units to form an endless mat-like chain.

23. A floor-surfacing machine, including a frame, an endless traveling scraping belt mounted upon the frame, bearing wheels upon which the frame is supported in free 50 rolling position, and power-driven bearing wheels adapted to be shifted into operation to propel the vehicle, the driving wheels being pressed to effective position by the operator of the vehicle.

24. A floor-surfacing machine, including a frame, an endless traveling scraping belt mounted upon the frame, bearing wheels upon which the frame is supported in free 60 rolling position, power-driven bearing wheels adapted to be shifted into operation to propel the vehicle, and means on which the operator steps to render the power driven wheels effective.

25. A floor-surfacing machine, including a 65 frame, an endless traveling scraping belt mounted upon the frame, bearing wheels upon which the frame is supported in free rolling position, and power-driven bearing 70 wheels adapted to be shifted into operation to propel the vehicle, the driving wheels being rendered effective by weight of the operator.

In testimony whereof I have signed my name to this specification.

EMIL B. GUNTHER.
